UNITED STATES PATENT OFFICE.

EDWIN SCOTT KINCANNON, OF SPOKANE, WASHINGTON.

BABY-WALKER.

1,072,959

Specification of Letters Patent. Patented Sept. 9, 1913.

Application filed November 29, 1912. Serial No. 734,011.

To all whom it may concern:

Be it known that I, EDWIN S. KINCANNON, a citizen of the United States, and a resident of Spokane, in the county of Spokane and State of Washington, have invented a new and Improved Baby-Walker, of which the following is a full, clear, and exact description.

My invention has for its design to provide a baby-walker having a body portion so formed as to afford proper abdominal and waist support for the child; and to provide a convenient seat portion in connection with the body part, as well as a head rest and arm rests, so formed and arranged as to promote the comfort of the child.

The invention also has for its design, the construction of the body part in a manner to permit of readily varying its size and to provide for various adjustments of the seat portion and the head rest.

It is also a design of my invention to provide a novel suspending means for the baby-walker, so constructed that the child will be induced to take exercise and support himself by means of his hands, above the floor, and without resting on the seat.

The invention will be more particularly explained in the specific description herein-after to be given.

Reference is to be had to the accompanying drawings forming a part of this specification, in which similar characters of reference indicate corresponding parts in all the views.

Figure 1 is a perspective view of a baby-walker showing a child in the act of walking; Fig. 2 is a similar view showing the child in the act of swinging himself from members of the suspension means, with his feet off of the floor; Fig. 3 is an enlarged perspective view, part of the suspension means being broken away; Fig. 4 is a plan view of the blank forming one of the body members; Fig. 5 is a rear elevation with parts broken out, the suspension means being omitted; Fig. 6 is a plan view without the suspension means; Fig. 7 is a transverse vertical section of the parts shown in Figs. 5 and 6; Fig. 8 is a plan view of the blank from which the seat portion is formed; and

Fig. 9 is a plan view of the blank from which the head rest is formed.

In constructing a baby-walker in accordance with the illustrated example, a body portion 10 is provided, composed of two similar members 10^a within which a child may be placed. To said body part is secured a strip comprising an integral back member 11, a seat portion 12, and a front connecting member 13. At the back of the body portion a head rest 14 is secured, and the sides of the body 10 are provided with arm rests 15. The baby-walker has suspending hangers 16 at each side, which depend from a spreader bar 17, connected by a chain 18 to a pulley or peripherally grooved roller 19, mounted to run on an overhead track rail 20, which may be secured to a ceiling or other overhead support in any suitable manner; in the drawings I have shown a bar 21 carrying the track 20. The said bar may be secured fixedly in place or the track directly fastened to any overhead support.

In the example shown each body portion 10^a is formed near one end with key-hole slots 22, and at the opposite end with two horizontal rows of similar slots 23. The overlapped portions of the two body sections have their slots 22 in registry, and buttons 24 engage the overlapped portions at the slots to hold the sections together, said slots and buttons being preferably disposed at the front. The mating rows of slots 23 at the opposite ends of the sections are also adapted to receive buttons 25 similar to the buttons 24, these being omitted from Fig. 7, in the interest of clearness. In the illustrated example I have shown buttons that are detachable from the body sections.

Each hanger 16, at a side of the baby-walker, comprises a pair of chains or equivalent flexible elements united by cross bars or rungs 26. One chain 16^a is connected to its respective body section 10^a at the junction of the side and back thereof, said side and back forming more or less of an angle. At the said angle a vertical series of key-hole slots 27 are produced in each body section 10^a, and the lower end of the chain 16^a is passed inward through any one of said slots 27, and then outward through an adjacent

slot, as shown best in Fig. 3, and the extreme end 16^b of the chain is united to an adjacent link 16^c of the body section by means of a key-ring 28. The companion chain 16^d of each hanger ranges downwardly and forwardly, the chains thus diverging at the lower ends, and to properly unite said chain 16^d to the adjacent body section 10^a, the latter is provided with an inclined series of key-hole slots 29, through which the chain is passed and secured by a key-ring 28^a, which engages the chain in a manner similar to the ring 28. The series of slots 23 make it possible to conveniently shift the buttons 24, and to contract or enlarge the size of the body part. Similarly, the series of slots 27, 29, for receiving the chains provide convenient means to secure the lower ends of the chains at different points on the body, and to adjust the height of the baby walker to suit the height of the child. It will be seen that by reason of the inclined series of slots 29, the chain 16^d may be shifted on a diagonal line as the overlapped front ends of the sections 10^a are adjusted by means of the slots 23 and buttons 24, and the chain connection will thus be maintained at the corners of the front and sides.

I provide additional slots of key-hole shape at 30, between the rows of slots 23 and a button 31 may be passed through the slots 30 of the respective body sections, through either one of a series of similar slots 32 in the back member 11, and through any one of a vertical series of key-hole slots 33 in the head rest 14. Thus the back member 11 and the head rest 14 may be adjusted vertically, relatively to the body sections 10^a. There is furthermore formed in the front member 13 of the seat a vertical series of key-hole slots 34, any two of which may receive the buttons 24 that unite the overlapped front ends of the body sections. The head rest 14 is offset rearwardly so that the upper portion 14^a is set back, providing a horizontal intermediate portion 14^b, to support a pillow 35, which may be tied in place by a cord 36 passed around said pillow and passed through cord-holes 37 in the upper end of the back rest.

Each arm rest 15 is formed by returning on itself a strip 38 which fits over the upper edge of each body section 10^a, and a clamp plate 39 extends across one of the return members of said strips 38, the ends of the clamp plate being passed through slots 40 in the body sections, and through the inner member of the strip 38, and bent down on the latter as at 39^a (Fig. 7). A covering 41 of soft material is laid over the strip, both at the inner and outer surfaces of said strip, and is pasted or otherwise suitably fastened in position to afford a cushion.

I prefer to employ indurated fiber board 65 in manufacturing the body sections, the head rest, and the depending member comprising the back 11, the seat 12, and the front member 13, since said material has the desired rigidity to withstand hard usage 70 and to prevent wear at the slots; also it cannot readily be damaged by the child, and will maintain its form; moreover, the material enables me to construct the article at a minimum cost.

It will be obvious that with the described adjustment of the depending portion, the seat may be raised or lowered readily, and the rungs or cross bars 26 of the hangers 16 enable the child to grasp the runner at 80 different heights and support himself by his arms, with his feet raised from the floor, as in Fig. 2.

In the preferred form the hangers 16 are provided at the upper ends with saddles 42 85 that rest on the spreader bar 17, the saddles being formed of indurated board or other stiff material corresponding with the material entering into the body portion, head rest, etc. It will be observed that the back member 11 is broader than the seat member 12, said seat member and the front member being of reduced width so as not to give discomfort to the child.

Having described my invention and a 95 practical means of carrying the same into effect, I would state in conclusion that I do not limit myself strictly to the mechanical details herein illustrated, since manifestly the same can be considerably varied without departure from the spirit of the invention.

Having thus described my invention, I claim as new and desire to secure by Letters Patent:—

A baby walker comprising a body portion 105 formed of separate sections of stiff material overlapping at the front and rear, each section being provided at one end with a pair of keyhole slots spaced vertically, at the opposite end with spaced horizontal series of 110 keyhole slots, a vertical series of keyhole slots adjacent to the horizontal series, an inclined series of keyhole slots between said vertical series and the first mentioned pair of keyhole slots, and with additional keyhole slots between the mentioned horizontal series of slots; a depending strip comprising a back member having a vertical series of keyhole slots and overlapping the body portion, a seat member projecting forwardly 120 from the said back member, and a front member formed with a vertical series of keyhole slots at its upper end and overlapping the body portion, fastening means engaging in the mentioned pairs of slots in the 125 respective body sections and in slots of the front member, additional fastening members engaging in alining slots of the hori-

zontal series in the respective body sections, and an additional fastening device engaging a slot of the mentioned back member and in alining slots in the body sections between the mentioned horizontal series of slots.

In testimony whereof I have signed my

name to this specification in the presence of two subscribing witnesses.

EDWIN SCOTT KINCANNON.
